US00D620915S

(12) **United States Design Patent**
Brabander

(10) **Patent No.:** **US D620,915 S**
(45) **Date of Patent:** **** Aug. 3, 2010**

(54) **HANDSET**

(75) Inventor: **Hans-Henning Brabander**, Munich (DE)

(73) Assignee: **Gigaset Communications GmbH**, Munich (DE)

(**) Term: **14 Years**

(21) Appl. No.: **29/340,053**

(22) Filed: **Jul. 13, 2009**

(30) **Foreign Application Priority Data**

Jun. 17, 2009 (EM) 001550773

(51) **LOC (9) Cl.** **14-03**

(52) **U.S. Cl.** **D14/147**

(58) **Field of Classification Search** ..... D14/137, D14/138 R, 138 AA, 143–144, 147–148, D14/156, 218, 247–248, 341–347, 390, 399, D14/455–456, 496; D13/164, 168; D21/329, D21/331, 333, 517; 343/702; 348/14.01–14.02; 361/814; 379/433.01–433.13; 439/165; 455/90.3, 556.1–556.2, 566, 575.1, 575.3, 455/575.4; 345/167, 168, 169
